(57) **CLAIM**

The ornamental design for a removable modular attachment system, as shown and described.

DESCRIPTION

FIG. 1 depicts a perspective view of male and female portions of a removable modular attachment system disconnected from each other, according to an embodiment of the invention.

FIG. 2 depicts a front view thereof, according to an embodiment of the invention.

FIG. 3 depicts a back view thereof, according to an embodiment of the invention.

FIG. 4 depicts a left side view thereof, according to an embodiment of the invention.

FIG. 5 depicts a right side view thereof, according to an embodiment of the invention.

FIG. 6 depicts a top view thereof, according to an embodiment of the invention.

FIG. 7 depicts a bottom view, according to an embodiment of the invention; and,

FIG. 8 depicts a perspective view of the male and female portions of the removable modular attachment system connected to each other, according to an embodiment of the invention.

In the drawings, the broken lines adjacent to the shaded surfaces represent the boundaries of the claimed portion of the design and form no part thereof. All other broken lines show portions of the removable modular attachment system that form no part of the claimed design.

1 Claim, 8 Drawing Sheets

Related U.S. Application Data

which is a continuation of application No. 17/545, 957, filed on Dec. 8, 2021, now Pat. No. 11,330,908.
